MOLDABLE AND ADJUSTABLE DISPLAY FORM

Ida R. Rock, Brooklyn, N. Y., assignor to Silhouette Form Co. Inc., New York, N. Y., a corporation of New York

Application June 26, 1935, Serial No. 28,406

8 Claims. (Cl. 223—68)

The present invention relates to garment forms as used for displaying dresses, coats, suits, knitted wear, foundation garments, etc.

Present day practice is to employ, for the display of garments, a rigid, inflexible form of wood or the like in association with the conventional display standard or other support. These types of forms are shaped, in certain instances, to simulate a front or side profile of the human body. Although serving as a support for a garment, they do not, however, attempt to fill out said garment to afford the viewer a true representation thereof.

Merchants in one neighborhood or locality may have to cater to purchasers who prefer a garment with one style of hip and waist lines, while merchants in another locality find it necessary to emphasize certain other lines and contours even for garments of the same size.

The invention contemplates the provision of a hollow form faithfully simulating the front half of the human torso and made of fibre, buckram or the like, to afford substantial rigidity and a fair degree of pliability. It is also contemplated to mount such a form upon an adjustable stand or pedestal, or support it from a conventional coat hanger or other support, so it may be placed for show purposes in a manner whereby the front of a garment thereon is exposed to view. Forms of this type may be made in all the necessary sizes and shapes in conformity with sizes and shapes of the human body which they simulate.

For the purposes of economy and for affording more universal use of any one form, and to afford each individual garment-displayer the opportunity of exercising his own personal judgment, skill or whim as to the shape he wishes to impart to the garment to be displayed, in order to induce the prospective customers of his particular locality to desire and purchase the garment, the invention seeks to provide a form of the above mentioned character which is easily and readily adjustable to various hip and waist contours. In this manner, two or three sizes of forms may each be varied in size and shape to provide, in effect, eight to twelve, or more sizes of display forms.

The invention also contemplates the provision of readily accessible, simple and effective means for varying the size and shape of a display form of the hollow pliable type herein contemplated.

Another contemplated feature of the invention is to provide simple inexpensive means for securing said form to a stand or pedestal and to

provide means in the manner of clips placed in the hollow of the form for engaging portions of the garment draped upon the form for the purpose of retaining said garment in proper and non-displaceable relation thereon. 5

The invention, as exemplified in the accompanying drawings, suggests several means for realizing the foregoing objects of the invention.

In the drawings:

Fig. 1 is a perspective view, as seen from the rear, of a preferred embodiment of display form incorporating features of the invention.

Fig. 2 is a cross-sectional view as taken along the line 2—2 of Figure 1.

Fig. 3 is a similar view showing the hip portion of the form bent to a smaller size.

Figs. 4, 5, and 6 are cross-sectional views of alternate forms of the invention.

Fig. 7 is a fragmentary rear view showing still another embodiment of the invention. 20

Fig. 8 is a view similar to Figure 1, of an alternate embodiment of display form including modified means for varying the size and shape of the form.

Fig. 9 is a cross-sectional view of still another 25 means for varying the size and shape of a display form.

Fig. 10 is a fragmentary rear view thereof.

In greater detail, the form 10 comprises a hollow body simulating the front of the human torso 30 and including a bust portion 11, a waist portion, 12, and a hip portion 13. In the usual manner, the form is made of relatively stiff, flexible material such as fibre, papier-mâché, or buckram which is capable of being bent though always 35 tending to resume its initial shape.

In a manner well known, the form may be supported upon an adjustable stand or pedestal 14 by means such as the clamp 15, said stand being provided with a hanger 16 for the purpose 40 of supporting shoulder portions of a garment arranged on the form.

To suit the distance between the shoulders and the waist line of the garment, the form may be 45 vertically adjusted, relative to the shoulder hanger on the stand or other support, and hence no adjustments therefor are necessary in the body of the form. It is desirable, however, to adjust the dimensions of the form particularly at the 50 hip and waist portions 12 and 13 respectively. A preferred form of means for this purpose is shown in Figures 1, 2 and 3 and comprises a bendable member 17 in the form of a strip of metal or the like secured to the inner portion 55

of the form as shown by means such as the rivets or eyelets 18 at the hip portion.

Comparison of Figures 2 and 3 will clearly disclose how the size of the hips of the form may 5 be varied by bending the strip 17 either by forcing the ends thereof away from or toward each other.

The strip 17 though easily bendable, will remain in whatever position it is placed and, therefore, 10 retaining the hip portions of the form in similar position.

The clamp 15 is preferably formed as part of a metal strip 15^a which, like the strip 17 may also be bendable so that adjustments of the waist 15 portion of the form, at which point said strip 15^a is secured, may be made in the manner above described.

In addition, the strip 15^a may be provided adjacent each of its ends with a spring clip or 20 the like 15^b into which may be tucked side portions of the garment which is draped on the form to effectively and securely support said garment properly thereon.

If desired, the strips 15^a or 17 may be omitted 25 and tie-back strings 19 secured at the edges of the form as at 20 may be employed for varying the size of the hip portions. This is shown in Figure 4. In such case clamp 15 may be secured directly to the form.

30 Another manner of carrying out the invention is shown in Figure 5, wherein a turnbuckle 21 engages oppositely threaded rods 22 pivoted to the edges of the form at 23.

In the previously described forms of the invention 35 the sizes of the hip portions were varied by either drawing the edges of the form towards each other or by spreading them apart, or by utilizing the inherent tendency of the form to resume its initial position as shown in Figure 4. The hip 40 sizes may also be lessened by simultaneously pressing against the center of the form from the rear and pulling the edges of the form. This embodiment of the invention is shown in Figure 6 in which a cross bar 24 is fastened at its ends to the form as at 25 and provided with a screw seat 45 for a screw 26 which may impinge either on the form directly or upon a member 27 secured to the form at a medial portion thereof. As the screw is turned, the bar 24 is bowed and therefore 50 draws the edges of the form towards each other. In the drawings, the form is shown at its maximum size.

Associated with any of the forms of the invention above described, there may be employed metal strips 28, secured to the form adjacent its side edges and extending to a length sufficient to 55 modify the entire hip lines of the form when the size varying means are operated. These strips also may be separately bendable if desired or 60 they may be spring members sufficiently flexible so the hip lines are smooth in any adjusted position of the form.

The form, as previously described, is used in association with a hanger 16 for proper support of a garment. However, the form may be made with shoulder portions 30 terminating in a neck portion 31 as shown in Figure 8 to obviate the use of the mentioned hanger 16 and to present to the viewer a more complete simulation of the human 70 torso. This type of form may be mounted as heretofore described or may simply be hung upon the top end of a stand or over the hanger, the inner portion of the neck or the shoulders serving for this purpose.

75 In Figure 8 is also disclosed still another type of

means for varying the size and shape of the form at the hip and waist portions. In this instance, the strips 28 may be connected by an arched metal strip 32 bendable as desired for modifying the contour of the form at adjacent portions, the 5 strips 28 being either bendable or sufficiently springy for the same purpose.

Still another form of adjusting means is shown in Figures 9 and 10 wherein the bendable strip 17 is provided at each end with a hinge eye 33. 10 To each eye is hinged a strip 34, one being provided with a screw seat 35 and the other with an adjusting slot 36, a shouldered screw 37 being employed for clamping the strips 34 and any 15 adjusted relation of the form. The strip 17, in this form of the invention, may be omitted and short members having hinge eyes 33 may be employed instead.

As can be seen from the foregoing, the invention 20 is capable of realization in many ways. Hence this specific disclosure which is capable of modification by skilled persons, should not tend to restrict the scope of the following claims. Whatever restrictions are imposed should rather be based upon the prior art.

25 What is claimed as new and desired to secure by Letters Patent, is:

1. A display form for garments comprising an integral flexible hollow body of sheet material simulating the front of the human torso, and a 30 bendable nonresilient member secured to an inner portion of said body transversely thereof and spaced from the upper and lower edges of said body whereby bending said member will flex adjacent portions of said body to vary the size 35 thereof.

2. A display form for garments comprising an integral flexible hollow body of sheet material simulating the front of the human torso, a bendable non-resilient member secured to an inner 40 portion of the body intermediate the upper and lower ends thereof and transverse thereto, and a substantially vertically disposed strip member secured adjacent each vertical edge of the body along the hip line whereby bending said bendable 45 member will flex adjacent portions of said body to vary the size thereof, said strip members acting to modify the contour of said adjacent portions of the body in accordance with the degree of bending of the bendable member.

3. A display form for garments comprising an integral flexible hollow body of sheet material simulating the front of the human torso, a bendable non-resilient member secured to the body intermediate the upper and lower ends thereof and transverse thereto, and a substantially vertically disposed strip member secured adjacent each vertical edge of the body along the hip line whereby bending said bendable member will flex adjacent portions of said body to vary the size thereof, said 55 strip members acting to modify the contour of said adjacent portions of the body in accordance with the degree of bending of the bendable member.

4. A display form for garments comprising a 60 flexible integral hollow body of sheet material simulating the front of the human torso, means for varying the size of a portion of said body comprising a bar having its ends secured to the inner side of the body and adjacent the vertical 65 edges thereof, and means connected to said bar for bowing the bar and thereby flexing adjacent portions of said body.

5. A display form for garments comprising a 70 flexible integral hollow body of sheet material 75

- simulating the front of the human torso, means for varying the size of a portion of said body comprising a transverse bendable member disposed on said body intermediate the upper and lower extremities thereof, and substantially vertically disposed members secured to and adjacent the side edges of the form at the hip line, the ends of said transverse member being secured to an intermediate portion of the said vertical members.
6. A display form for garments comprising a flexible integral hollow body of sheet material simulating the front of the human torso, means for varying the size of a portion of said body comprising a transverse bendable member attached to said body intermediate the upper and lower edges thereof, and substantially vertically disposed spring members secured to and adjacent the side edges of the form, the ends of said transverse member being secured to the said vertical members intermediate their ends.
7. In combination with a garment supporting and display stand having lateral extending arms on the upper portion thereof, a display form detachably and adjustably mounted on the standard of the stand, said display form comprising a flexible integral hollow body of sheet material simulating the front of the human torso, means for varying the size of the waist area of said form comprising a bendable strip secured transversely to the concave side of the form in the region of the waistline, clamping means extending from said strip for adjustable engagement with the standard of the stand, and means for varying the size of the hip area comprising a bendable member secured transversely to the concave side of the form at the hip region.
8. In combination with a garment supporting and display stand having lateral extending arms on the upper portion thereof, a display form detachably and adjustably mounted on the standard of the stand, said display form comprising a flexible integral hollow body of sheet material simulating the front of the human torso, means for varying the size of the waist area of said form comprising a bendable strip secured transversely to the concave side of the form in the region of the waistline, clamping means extending from said strip for adjustable engagement with the standard of the stand, means for varying the size of the hip area comprising a bendable member secured transversely to the concave side of the form at the hip region, and a substantially vertically disposed spring member secured to and adjacent the side edges of the form and extending from the region of the waistline to the region of the hip line and attached to ends of the bendable member, whereby bending said bendable member will flex adjacent portions of said body to vary the size thereof, said spring members acting to modify the contour of said adjacent portions of the body in accordance with the degree of bending of the bendable member.
